UNITED STATES PATENT OFFICE.

SAM PHILLIPS, OF SHERRILL, NEW YORK.

SWIVEL SNAP-HOOK.

SPECIFICATION forming part of Letters Patent No. 720,378, dated February 10, 1903.

Application filed October 28, 1902. Serial No. 128,513. (No model.)

To all whom it may concern:

Be it known that I, SAM PHILLIPS, of Sherrill, in the county of Oneida, in the State of New York, have invented new and useful Im-

5 provements in Swivel Snap-Hooks, of which the following, taken in connection with the accompanying drawings, is a full, clear, and exact description.

This invention relates to improvements in 10 swiveled snap-hooks.

My object is to reduce the cost of manufacture by reducing the number of parts and assembling the same without rivets or bolts and at the same time to increase the strength 15 and freedom of operation of the parts one upon the other.

To this end the invention consists in forming and combining the parts as hereinafter fully described, and pointed out in the claims.

20 Referring to the drawings, Figure 1 is a perspective view of my improved swivel snap-hook. Figs. 2 and 3 are sectional views taken on lines 2 2 and 3 3 of Fig. 1. Fig. 4 is a perspective view of the detached hook-piece.

25 Fig. 5 is a perspective view of the extended detached bar for forming the swivel-head. Fig. 6 is a similar view of the detached spring retainer-piece.

Similar reference characters indicate cor- 30 responding parts in all the views.

This swivel snap-hook comprises three dis- tinct parts—viz., a main hook-shaped body 1, a spring retainer-piece or keeper 2, and a swiveled head 3, each of which parts is 35 formed of a single piece of suitable metal and assembled in a manner hereinafter described. One end of the main body 1 is formed with a hook 4, and its other end is provided with a pair of slots or elongated substantially paral- 40 lel openings 5 and a T-shaped extension 6. The keeper 2 consists of a piece of spring metal having one end formed with oppositely-projecting arms 7, inserted through the openings 5 from one face of the main body of the 45 hook and overturned or clenched against the opposite face of said main body, thereby firmly locking the two parts together. The opposite end of the keeper is free to spring inwardly and is normally tensioned to engage 50 the inner face of the hook 4. The swiveled head 3 is also formed of a single piece of wrought or other bendable metal, and its op- posite ends 8 are flattened and provided with

openings 9, which are cut one way long enough to receive the head of the T-shaped exten- 55 sion 6 when assembling the part of one upon the other.

In assembling the swivel-head 3 upon the T-shaped extension 6 the part between the flattened ends 8 is bent into the desired form— 60 as, for instance, a ring—and the flattened ends are folded or lapped one upon the other, with their openings alined with each other, whereupon said open ends are slipped over the T-shaped extension 6, and the side walls 65 of the openings 9 are then compressed around the reduced portion of the extension, so as to make the openings 9 smaller either way than the head of the extension.

The spring-keeper and swivel-head are thus 70 attached to the main body without rivets or bolts, each part carrying its own fastening means, and all of the parts may be readily and economically manufactured and assem- 75 bled to produce a much cheaper and stronger device than those now in use.

Having thus described my invention, what I claim, and desire to secure by Letters Patent, is—

1. A swivel snap-hook including a main 80 hook-body having a T-shaped head, and a swivel-head consisting of a bar having its op- posite ends flattened and provided with open- 85 ings, said open ends being lapped one over the other with their openings alined and slipped over the T-shaped head, and their walls com- pressed around the reduced portion of the T- shaped head to hold the parts from detach- 90 ment one from the other.

2. A swivel snap-hook comprising a main 90 hook-body having a pair of elongated slots and a T-shaped extension, a spring-keeper formed with laterally-projecting arms in- 95 serted in the slots and clenched therein, a swivel-head consisting of a bar having its op- posite ends flattened and provided with open- 100 ings alined with each other, the T-shaped head being inserted in said openings and the walls of the openings being compressed upon the reduced portion of the T-shaped head.

In witness whereof I have hereunto set my hand on this 2d day of October, 1902.

SAM PHILLIPS.
